JOSEPH E. ANDERSON, OF COSCOB, CONNECTICUT.

TRAIN-CONTROL SYSTEM.

1,303,227.

Specification of Letters Patent.

Patented May 13, 1919.

Application filed December 9, 1915. Serial No. 65,904.

To all whom it may concern:

Be it known that I, JOSEPH E. ANDERSON, a citizen of the United States of America, residing at Cos Cob, in the county of Fairfield and State of Connecticut, have invented certain new and useful Improvements in Train-Control Systems, of which the following is a specification, reference being had therein to the accompanying drawing.

10 This invention relates to train control systems, and its object is to provide an electrical train control system which is simple, positive, reliable and efficient, and which may be economically installed and operated.

15 The invention consists in the features of construction, combination and arrangement of parts more fully hereinafter described, reference being had to the accompanying drawings, in which—

20 Figure 1 is a diagrammatic view showing the track circuits of several blocks of a train control system embodying my invention;

Fig. 2 is a similar view showing the arrangements of parts of the system at a 25 switch point;

Fig. 3 is a plan view of a portion of the track, showing in detail the construction of the stop rail;

Fig. 4 is a cross section through one of the 30 plates and magnets of the stop rail and showing the position of one of the magnets of the actuating means upon the locomotive relative thereto;

Fig. 5 is a side elevation of the parts of 35 the stop rail shown in Fig. 4; and

Fig. 6 is a diagrammatic view of the actuating and indicating means upon the locomotive.

Referring to the drawings, (see Fig. 2,) 40 A and A' and B and B', respectively, designate the rails of a main line and siding or branch line, C a switch point at the intersection of said lines, and D—D', E—E, the wires of two main circuits supplied with 45 current from suitable sources of energy, the said wires D—D' constituting main supply conductors of block circuits arranged at the block sections or divisions throughout the system. The rails of the system are insulated from each other between blocks, as 50 shown at F, and, for purposes of illustration, five blocks or stations of the main line, denoted F', F², F³, F⁴ and F⁵ (see Fig. 1), are disclosed in the present instance, and

corresponding portions of a siding or branch track will be hereinafter described.

Each block circuit is normally open. Each block comprises one one-point relay g^1 and one four-point relay g^{12} , also the necessary wires as therein indicated which connect these relays with the track circuit in that block. G, G', G², G³, G⁴ indicate electric circuits controlling and operating in conjunction with their respective blocks F, F², F³, F⁴, F⁵. With each of these block 60 circuits cooperates a control or stop rail H. This rail H extends centrally between the track rails and consists of a series of face-plates H' (see Fig. 4) making almost a continuous rail of magnetic influence. Attached to the underside of each face-plate is a magnet H² arranged in a non-magnetic box or casing H³. The magnets of the control or stop rail of each block are wired up in parallel relation with the track circuit in 65 the distant (second) block ahead which controls the block in question. An important fact concerning these magnets is that their north poles face upward, and that under certain conditions the magnets are adapted 70 to be energized. When there is an absence of electricity in the magnets H², then it is an indication of danger somewhere, and the stop rail is deenergized and presents itself 75 only as a magnetic conductor.

Each block circuit G comprises conductors g and g' , which are connected with a single point relay or electromagnet g^2 controlling a switch g^3 . The conductor g leads from this magnet back to one of the track 80 rails A of the second block behind, while the conductor g' leads from said magnet to a point for coöperation with one of the conductors g^4 . The switch g^3 normally connects the conductors g^5 and g^6 , which latter 85 has arranged therein a four point relay or electromagnet g^{12} , controlling switch members g^{13} , g^{14} , g^{15} , and g^{16} . The conductor g^6 connects with the conductor g^7 which is normally connected by the switch member 90 g^{14} with conductor g^8 , while the conductor g^9 is normally connected by the switch member g^{15} with the conductor g^{10} leading to the advance conductor g of the second or distant block ahead. The conductor g^{11} connects with switch member g^{13} , while conductor g^4 is normally connected with conductor g' by switch member g^{16} . The switch 95 100 105 110

member g^{13} of each block circuit is normally open and is adapted to be closed by the magnet g^{12} when the latter is energized and opens the other switch members, to connect 5 the conductor g^{11} with one of the conductors h' of the stop rail circuit, including the conductor h , which conductors g^{11} and h lead respectively to the rails A—A' of the distant block or second block ahead. The 10 rails A—A' of each block are adapted to be electrically connected or bridged by the wheel trucks of a train and form with the conductors g , h and h' a train controlled track circuit which is designed for coaction 15 with actuating mechanism on the locomotive for track condition indicating and train controlling purposes.

The block circuits F^e and F^f shown in connection with the siding $B-B'$ and switch point C are the same as those in the main line above described, with the exception of the inclusion of an electric switch I associated with the switch point throwing mechanism for throwing the siding block circuits into and out of working connection with the main line block circuits, and with the further exception of the employment of an auxiliary circuit for controlling the speed of the train. The switch I is a three-point switch which is movable to connect different sets of branches of the conductors g and g^7 for all main-line and main-and-siding connections. The speed controlling circuit referred to consists of a speed controlling bar or rail J (in duplicate for opposite direction travel) which is similar to the stop bar and has its magnets arranged in a normally open speed governing circuit including a conductor j leading to the main conductor E' , and conductors j' and j^2 (see Fig. 2) leading to the main conductor E and adapted to be connected by a relay or switch consisting of an electromagnet j^8 and armature switch member j^4 , said magnet being arranged in the conductors j^9 .

40 The actuating or controlling mechanism on the locomotive, which is clearly shown in Fig. 6, comprises a generator L, driven from one of the wheels or axles of the locomotive
50 and from the poles of which lead the main conductors l, l', which conductors form part of a general normally-open controlling and indicating circuit including stop and speed controlling circuits, governed by main electromagnets M' and N'. These magnets are mounted upon pivoted levers M² and N² normally sustained by springs M³ and N³ and the free ends of which are, respectively, movable between sets of contacts m—m' and
55 n—n', so that said levers, which are connected with the primary coils of the main magnets, form switches controlling said circuits. The stop magnet M' is located in the center line of the engine for co-operation
60 with the stop rail H, while the speed mag-
65

net is located to the right or left (or both) of the engine for coöperation with the speed rail or rails J. On the switch levers are armature plates m^2-n^2 for coöperation with holding magnets m^3-n^3 whereby said 70 switch lever when drawn downward are held down, as hereinafter described.

The control magnets M' — N' have their north poles facing downwardly and are normally energized by the supply of current from the generator and are held sustained by the springs at a predetermined elevation, each magnet being free to move downward from a normal position, in which they engage the contacts m and m' , to a position in which they engage the contacts m^2 and m' , and the armatures m^2 — n^2 are attracted and held by the electromagnets m^3 — n^3 , the magnets being thus mounted so as to be attracted or repelled by the rails H and J while never having actual contact therewith. The magnet M' controls a series of solenoids M^4 , M^5 and M^6 , the cores m^4 , m^5 and m^6 of which are connected with handles or operating levers o , o' and o^2 of valves O , O' and O^2 , the valves O and O' being arranged in the steam supply connections to control the supply of steam to the engine cylinders, while the valve O^2 is disposed at a suitable point in the air brake mechanism, said valves being operatively connected with valve closing springs o^3 acting upon the magnet cores. The magnets N' control a similar series of solenoids N^4 , N^5 and N^6 , the cores n^4 , n^5 and n^6 of which are connected with handles or levers p , p' and p^2 of valves P , P' and P^2 , operatively connected with valve closing springs p^4 . The valves P and P^2 are arranged in the air brake system, while the valve P' is arranged in the steam supply system of the locomotive, and these valves are adapted to be controlled to reduce and govern the speed of the locomotive when approaching and running over a switch point.

The magnets M^4 and N^4 have one of their terminals connected with the positive and negative conductors l and l' leading from the generator L , and the other terminals of these magnets are connected by conductors q , q' , q^2 and q^3 with the terminals of the electromagnets M' and N' , the arrangement being such that the magnets M' , N' , M^4 and N^4 are normally in circuit with and supplied with current from the generator L when the locomotive is in motion, and, consequently, the cores of the two last named magnets are attracted and hold the valves O and P open against the resistance of their springs u^3 and p^3 , and are released for action automatically when the generator L is rendered inoperative to effect the closing of the valves. The contact m , which is a distance clearance contact, is connected by a conductor r with a green or clear light r' , which is connected in turn with a recorder R connected by a con-

ductor r^2 with the conductor q' , the said lamp and recorder being connected in turn by a conductor r^3 with a red or danger signal lamp r^4 . The conductor r^3 leads to one of the terminals of the magnet m^3 , and has arranged therein the solenoids M^5 and M^6 , while a conductor r^5 leads from the other terminal of the magnet m^3 to the contact m' which is a danger signal contact. The contact n is an idle contact and simply serves as a stop to limit the upward movement of the lever N^2 , while the contact n' is a speed control and release contact and is connected by a conductor s with the valve lever o , which also operates as a release switch, normally engaging a switch contact s' which is connected by a conductor s^2 with one terminal of the magnet n^8 , the other terminal of which is connected by conductor t with a blue or other suitably colored switch indicating lamp t' and with the recorder R , all of the parts of the controlling devices on the locomotive being thus arranged for electrical control to govern the movements of the train according to conditions along the line of the trackway, as indicated by the elements of the track circuit hereinbefore described. The recorder R gives an indication for future observation and reference whenever the devices on the locomotive are affected by outside conditions, while the lamp r' , which is normally in use, is to indicate, when glowing, the fact that the track is clear for travel, while the red light, when glowing, indicates danger ahead and that the parts of the controlling mechanism have been operated to avert such danger, while the lamp t' when glowing indicates that the controlling mechanism at the switch point is in proper operation and the switch point has been fully thrown for the safe travel of the train, the speed of which is under automatic control during the entire travel of the train between the main and branch lines or vice versa. The function of the lever o in its action as a switch is to control that portion of the circuit in which the holding magnet n^8 is arranged to effect the deenergization of said magnet and release of the lever N^2 when the steam supply has been cut down and the speed of the train reduced to a certain degree.

In the operation of my improved automatic train control system, in the control of a train running upon a "straightaway" track, the entrance of a train or portion thereof into a block results in the examination of three conditions, to wit: first, whether or not there is a train occupying the distant block; second, whether or not the rails along the right of way in the distant block are in perfect condition, and, third, whether or not the electric circuit controlling the block is anywhere broken. If the distant block is occupied by a train or portion thereof, the

train will stop in the immediate block, or if the rails in the distant block are broken anywhere in their length the train will stop in the immediate block, or if there is no train in the distant block, and the rails are perfect, but the electric circuit controlling the immediate block is short circuited or broken anywhere, then the train will stop in the immediate block. Each train on its travel closes its own circuit as it travels and short circuits the second block behind, it being observed that the circuits are normally open and the stop rails normally deenergized, that each stop rail is energized upon the entrance of a train into its block and only so when the distant block is perfect and ready for occupation, the train being brought under control, under all conditions, upon the absence of electricity on the right of way. After being automatically stopped the train is automatically released and is then in the hands of the engineer, but not so until it has fully stopped. The automatic release above mentioned is accomplished in two separate ways: In the first case the control is released by the stopping of the train, since the current supplied by the generator ceases when the engine stops; and in the second case the automatic release is accomplished by reducing the speed of the train, so that the solenoid which maintains the steam valve open by the generation of electricity through the movement of the train releases the auxiliary magnet which holds the control after having passed the control rail on the right of way. The elements of the circuits on the locomotive are preferably inclosed, in practice, in a metal case or cabinet and under lock and key, so that neither the engineer nor any other unauthorized person can meddle with the apparatus.

It will be evident that as there is employed on the right of way a normally open track circuit at each block and extends to the stop rail two blocks in the rear, the stop rail in every block is controlled by the conditions in the distant block which is two blocks ahead. When there is no train in either of these two blocks, there is no electricity flowing through any part of this circuit, but when a train comes into the immediate block and closes its own block circuit, it also closes the circuit of the second block ahead. If this block ahead or distant block is not occupied and the circuits connecting thereto are perfect, then the examining train will be permitted to proceed by virtue of the fact that the stop rails will be energized.

Assuming, however, that the stop or control rail should be deenergized, and that the engine having the necessary control apparatus is passing over the said rail, since the rail is deenergized, it presents itself to the engine magnet as an ordinary length of iron

fastened to the roadway, and as the engine magnet is free to move downward it will be seen that said magnet will attract itself to the length of rail, but will not touch it as it does not move downward to a sufficient degree. In this operation there are no contact actions or sliding parts liable to cause trouble, damage or imperfect working, there being simply a magnetic field acted upon 10 by a magnetic conductor to bring about a change of conditions on the engine, whereby the control mechanism on the engine will be set into action. On the other hand, should the stop or control rail be magnetized, since 15 said rail is magnetized with north magnetism there will be a large field of magnetism existing the entire length of the rail. As the controlling magnet on the engine passing over the rail also presents a magnetic field 20 of north polarity, it will be evident that since both fields are of like polarity they will tend to repulse each other. Hence there will not be any change of conditions on the engine and the engine will proceed, there 25 being in this operation an avoidance of the actual contact of parts in the track-way and upon the locomotive, and the result being attained by the simple changing of a length of iron from a magnetic conductor to a 30 magnetized conductor with north magnetic polarity, so that a passing energized magnet will attract itself to the magnetic conductor or be repulsed by the magnetized conductor.

35 In the control of a train in taking a switch, it will be evident that no train can approach a switch located in the immediate block until it has tested the security of said switch. The train in approaching the switch 40 will perform the following examinations, to wit: first, whether or not said switch is properly set; second, if the switch is only half set the train on entering the home block will test the distant block containing the 45 switch and will be brought to a stop before it reaches said switch. If, in the first examination, the switch is found properly set, then as the train enters the immediate block containing the switch in order to make the 50 siding, it is automatically brought to a slow speed, for example, ten miles per hour. Even though the train passes far beyond the control rail it will still take the switch at the predetermined speed, after which it will 55 be automatically released and restored to the control of the engineer. All of these operations are accomplished and due to the presence or absence of electricity on the right of way. In this train control system 60 there are two distinct and separate electric feed circuits, one of high pressure and one of low pressure; the one termed the "X-battery circuit" and the other the "Y-battery circuit."

65 Assuming that a train has entered block F^3 and bridges the track rails therein, then the electricity will take the following course: from conductor D to conductor g^5 , relay magnet g^{12} , conductors g^6 and g^7 and through the tracks and train trucks (this is 70 the positive side of the X-battery; therefore current will not enter conductor g^9) thence through conductor g to relay g^2 and conductor g' (relay g^{12} not being closed, electricity passes through contact to 75 switch member g^{16}) and thence through conductor g^4 to main conductor D' , thus completing the circuit. In this operation it has been found that the block F^5 is not occupied by a train or portion thereof. Also it has 80 been found that the circuits connecting the units are perfect. In completing this circuit relay g^{12} in block F^3 breaks the low pressure Y-battery circuit to block F^3 and the circuit from block F' to conductor D' . Thus it is impossible for a train having entered the block F' to leave said block, because it cannot complete its own circuit. Again, relay g^{12} in block F^3 also closes the 85 track circuit to block F^5 so that conductor E is in connection with the contacts in relay g^{12} in block F^5 through conductors g^8 , g^7 and the track rails to relay g^2 and through the switch g^{13} to conductor h' and through 90 the stop rail H, then through conductor h and to and through the track rails (as this is the positive side of the Y-battery circuit the current will not pass to conductor g) and thence through conductor g^9 to main conductor E' . Thus the train in F^3 has 95 found that the tracks and circuits in block F^5 are in perfect condition because it has successfully closed the circuits and entered the electricity into the control or stop rail. The train in block F^3 does not there examine block F^4 , for it has previously done so when it was in F^2 . Furthermore, it has entered the same block F^3 , because when it was in block F' it there examined block F^3 . Hence it will be seen that every train 100 examines the distant block before it leaves the block it is occupying. If that distant block is occupied the examining train will stop in the home block because it is unable to receive electricity into its own control rail. Therefore, for a train to proceed everything must be in perfect communication and the distant block must not be occupied. If the reverse of either or both of these conditions exist, then the train will be caused to stop 110 since there is no electricity on the right of way. 115

In the operation of this train control system, with regard to the relation of a switch to the main line track, reference is made to 125 Figs. 1 and 2 of the drawings, Fig. 1 showing the switch layout, in such a way as to form the continuation of either the main line or the siding, whichever condition may be under consideration.

In the first place, beginning with Fig. 1, we will assume that a train has entered block F^4 and that the despatch orders of this train are such that it is to take the siding $B-B'$, Fig. 2, at a predetermined speed of ten miles per hour. The train having entered block F^4 closes the following circuit: battery circuit X in block F^4 , conductor g^5 , contact g^8 , relay g^{12} , conductors g^6, g^7 , then rail A^1 , through the engine to A , then conductor g leading to mechanically controlled switch contacts I , then conductor g to relay g^2 , block F^6 , from here over g^1 , to relay contact g^{16} , on relay g^{12A} , and from here over conductor g^4 , to D^1 , the negative side of the X -battery. Thus we have completed the circuit involving relay g^{12} , in block F^4 , Fig. 1. In so doing, the relay g^{12} broke contacts g^{14}, g^{15}, g^{16} , and made contact g^{13} , which completed the circuit involving the stop rail H in block F^4 , Fig. 1. In tracing out this last named circuit, refer to Fig. 2; the electricity will come from the positive side of the Y -battery, over conductor E , to g^8 , block F^6 , contact point g^{14} , conductor g^7 , to rail A^1 , to conductor g^7 , leading to a contact on mechanical switch I , then over to g^1 , to the main line rail A^1 , in block F^8 , then over conductor g^{11} to relay contact g^{13} , in block F^4 , then over h^1 , to stop rail H in block F^4 , returning over conductor h , and continuing over main line rail A , to g , then to a contact on mechanical switch I , and over g , to siding rail A , and from here to g^{10} , then relay contact g^{15} , and finally over conductor g^9 , to the negative side of the Y -battery circuit, which is conductor E^1 . In completing this circuit involving the stop rail H in block F^4 , Fig. 1, we have examined the main line track and siding, also the switch location C , Fig. 2, and found that the track circuit therein is complete and that the switch is properly set to be taken. Thus the stop rail H in F^4 , Fig. 1, would be energized and the train will be able to proceed through block F^4 , Fig. 1, into block F^6 , Fig. 1.

Having entered block F^6 , Fig. 1, the train will close the following circuits, beginning with the X -battery at block F^6 , Fig. 1, from conductor D , g^5, g^8 , relay g^{12}, g^6, g^7 , rail A^1 , through the engine to rail A , conductor g , (see Fig. 2), then g^1 , Fig. 2, to switch contacts I , to block F^7 in the siding, (the train examines F^7 , Fig. 2, because the switch point C is set to be taken), (place Fig. 1 with relation to Fig. 2 so that block F^2 , Fig. 1, will represent block F^7 , Fig. 2); then the circuit will be continued over g , Fig. 1, then relay g^2 , conductor g^1 , to relay contact g^{16} , then over g^4 to D^1 , the negative side of the X -battery circuit.

Now the Y -battery circuit becomes active, since the circuit involving relay g^{12} , block F^6 , Fig. 1, (which is the main line track) is

completed. Beginning at the positive side of the Y -battery circuit E , in block F^2 , Fig. 1, (F^2 being electrically the continuation of F^7 , Fig. 2), the circuit continues over conductor g^5 , contact g^8 , relay g^{12} , conductors g^6, g^7 , then rail A^1 to g^{11} , (transfer Fig. 1, so that block F^6 , Fig. 1, will match up with block F^8 , Fig. 2, and form the main line tracks), then conductor g^{11} , Fig. 1, to contact g^{13} , block F^5 to conductor h^1 , then stop rail H , returning over h , Fig. 1, (transfer Fig. 1 to Fig. 2, so that block F^2 , Fig. 1, matches up with block F^7 , Fig. 2), then conductor h , Fig. 1, to track rail A , conductor g^{10} , relay contact g^{15} , then g^9 , and over to E^1 , which is the negative side of the Y -battery circuit. In completing this circuit involving stop rail H , block F^5 , of the main line track, we have found that the distant block in the siding is safe for travel. Thus the train can proceed into block F^8 , Fig. 2, which is the block containing the switch location C .

It will be noted that the speed controlling member J has not been mentioned heretofore, because it is desired not to energize this unit, since the speed of the train has yet to be reduced. Having entered block F^8 , Fig. 2, the engine closes the circuit involving g^{12A} , and the electricity will take the following course: conductor D of battery circuit X , to g^5 , contact g^8 , relay g^{12A} , conductors g^6, g^7 , rail A^1 , of the siding B , to g^7 , leading to contact on mechanical switch I , then g^1 , to A^1 of the main line tracks, then through the engine to A , conductor g , to mechanical switch contact, then g , to rail B , of siding B , then g , (place F^2 , Fig. 1, to match up with the siding, so that the block F^2 will represent the block beyond F^7 , Fig. 2), then conductor g , Fig. 1, block F^2 , through relay g^2 , conductor g^1 , relay contact g^{16} , then g^4 , then out over conductor D^1 , which is the negative side of the X -battery. Thus we have energized relay g^{12A} , Fig. 2, and made contacts g^{13} and g^{19} , involving the stop rail H , in block F^8 . In completing this circuit, the electricity takes the following course: battery circuit Y , Fig. 1, block F^2 , conductors E, g^8 , contact g^{14}, g^7 , rail A^1 , conductor g^{11} , (see Fig. 2), then g^{11} , Fig. 2, through contact g^{13} , then h^1 , to stop rail H , block F^8 , returning over h, g^{20} , to relay contact g^{19} , then g^{21} , (see Fig. 1), then conductor h , Fig. 1, rail A to conductors g and g^{10} , then contact g^{15} , to g^9 , and E^1 , which is the negative side of the Y -battery circuit. In completing this circuit we have energized the stop rail H , in block F^8 , Fig. 2, thus preventing the train from stopping in F^8 . Speed control rail J , being deenergized, will attract the speed controlling magnet N^1 , Fig. 6, thus reducing the speed of the train to the predetermined degree before it reaches the switch location C . Having passed the

switch C, the train will pass into block F⁷, Fig. 2. The train has now passed through and beyond the several blocks involving the switch location C.

5. In the second place, beginning with Fig. 1, we will assume that the train in question has entered block F⁴, Fig. 1, and that the despatch orders of this train are such that it is to continue on the main line track, past 10 the switch location C, in block F⁸, Fig. 2, (place Fig. 1 in relation with Fig. 2, so that block F⁸, Fig. 2, will be the block next beyond block F⁵, Fig. 1). The train being in 15 block F⁴ will naturally close the circuit involving relay g¹², in block F⁴; then the electricity will take the following course: D, which is the positive side of the X-battery circuit g⁵, g⁶, relay g¹², g⁶, g⁷, rail A¹, through the engine, rail A, conductor g, (see 20 Fig. 2), then conductor g, Fig. 1, in block F⁸; (the mechanically controlled switch contacts I, Fig. 2, would be changed from the completed circuits indicated, to the circuits shown uncompleted, by the fact that the 25 switch point C is positioned for the train to continue on the main line tracks), then through switch contacts I, to g, and relay g², then g¹, to relay contact g¹⁶, and g⁴, to D¹, which is the negative side of the X-battery 30 circuit. Thus relay g¹² becomes energized, and contacts made and broken as heretofore described. Next the Y-battery circuit will be considered. Beginning in block F⁸, Fig. 2, the circuit is E, g⁸, contact g¹⁴, 35 g⁷, a portion of the main line tracks, to conductor g¹⁸, mechanical switch I, g¹, to rail A¹, then g¹¹, to (see Fig. 1), contact g¹³, h¹, stop rail H, in block F⁴, then h, (see Fig. 2), then conductor h, Fig. 2, to rail A, then conductor g, mechanical switch I, conductor g, section of rail A, to second conductor g, to 40 g¹⁹, contact g¹⁵, g⁹, and E¹, which is the negative side of the Y-battery circuit. Thus we have completed the circuit involving stop rail H, in block F⁴, Fig. 1. The train now 45 is permitted to pass into block F⁸.

Block F⁵, Fig. 1, and block F⁹, Fig. 2, bear the same relation to each other as do any other two alternate blocks hereinbefore described. I have refrained from inserting the details of block F⁹, because of the natural confusion of the multiplicity of lines. It will be seen from the previously described alternate blocks that if block F⁹ is clear the 50 train in block F⁵ will receive the proper indication in its stop rail H, and thus be permitted to pass into block F⁸, Fig. 2.

Having arrived in block F⁸, the train will bridge rails A and A¹ and close the circuit 55 leading to relay g¹², in F⁸. In tracing this circuit, begin at battery circuit X on conductor D, then g⁶, contact g⁸, relay g¹², g⁶, relay j³, to g⁷, rail A¹, to conductor g¹⁸, mechanical switch I, g¹, rail A¹, through the engine, rail A, conductor g, mechanical switch 60

I, conductor g, to rail A, then g, to relay g², block F¹⁰, conductor g¹, contact g¹⁶, then g⁴, to D¹, which is the negative side of the X-battery circuit. Thus the relay g¹², to stop rail H, and relay j³, to speed rail J in block 70 F⁸, have become energized and in so doing each relay made and broke contacts. (The object now is to energize the stop rail H and the speed rail J, in block F⁸, so that the respective engine magnets M¹ and N¹, Fig. 6, 75 will not change their respective normal positions, and thus permit the train to proceed without affecting its speed). Next the battery circuit of conductor E is continued over g⁸, block F¹⁰, Fig. 2, then g¹⁴, g⁷, rail A¹, g¹¹, to 80 contact g¹³, in block F⁸, then g¹, to stop rail H, returning over h, to track rail A, then g, to contact g¹⁵, g⁹, to conductor E¹, which is the negative side of the Y-battery circuit. Thus we have energized the stop rail H, in 85 block F⁸. Referring to the speed control rail J, the circuit begins from conductor E, of the Y-battery circuit, to j², contact j⁴, conductor j¹, to stop rail J, (stop rail J is constructed in duplicate and electrically connected in parallel for affectation on the engine, whichever end of the engine may be traveling forwardmost), then returning over j, to E¹, which is the negative side of the Y-battery circuit. Thus we have energized the 90 speed rail J, and prevented the speed controlling mechanism on the engine from operating. This, of course, will permit the train to proceed without reducing its speed. The train now is free to pass into block F⁹, the 100 safety of which was ascertained in block F⁸, Fig. 1.

In all the foregoing description, we have considered that the track in advance of the train in question was at all times clear for 105 travel. The opposite of any one of these descriptions would be caused by a train occupying the distant block, a broken rail, a short circuit, or an open circuit, anywhere within the control of the train in question.

Thus it will be clearly seen that the control of the train in question is effected by the attraction of the engine magnets by and to a length of iron (called the stop rail) or the non-attraction of the engine magnets by the 115 repellent action due to the magnetization of this length of iron.

I claim:

1. In an electrical train control system, a series of blocks for cooperation with a train magnet, each of said blocks provided with a track circuit having a train controlling member therein comprising a normally magnetic conductor, said track circuit including the rails of a block in advance of the train controlling member, said member being energizable by the energization of the circuit in which it is arranged to form a magnetized conductor for repelling said train magnet.

2. In an electrical train control system, a 120

- series of blocks, for cooperation with a train magnet, each of said blocks provided with a train controlled track circuit therein and each having a train controlling member therein comprising a normally magnetic conductor, said track circuit including the rails of a block in advance of the train controlling member, said member comprising a rail consisting of conducting sections, each having 5 nets being arranged in parallel with the track circuit in which the member is disposed, and being energizable by the closing of said circuit to convert said rail from a magnetic to a magnetized conductor. 70
- 10 6. In an electrical train control system, a series of blocks each comprising a section of trackway and a normally open circuit including the rails thereof and adapted to be closed by the bridging of the rails by the 75 rolling stock, and each having arranged therein a train controlling member, said track circuit including the rails of a block in advance of the train controlling member, each circuit including connections for influencing a train controlling member in a block behind for a train controlling action and determining by the presence or absence of current in the local block the condition of a track circuit ahead. 80
- 15 7. In an electrical train control system, a series of blocks each provided with a train controlled open track circuit therein and each having a train controlling member therein, said track circuit including the rails 85 of a block in advance of the train controlling member, said member normally constituting a magnetic conductor and being energizable by the closing of the track circuit in which it is arranged to form a magnetized conductor. 90
- 20 8. In an electrical train control system, a series of blocks each comprising a section of trackway and a normally open circuit including the rails thereof and adapted to be closed by the bridging of the rails by the 95 rolling stock, and each having arranged therein a train controlling member, said circuit including the rails of a block in advance of the train controlling member, said member comprising a normally magnetic sectional conductor energizable by the closing of the track circuit in which it is arranged to form a magnetized conductor. 95
- 25 9. In an electrical train control system, a series of blocks each comprising a section of trackway and a normally open circuit including the rails thereof and adapted to be energized by the bridging of the rails by the 100 rolling stock, and each having arranged therein a train controlling member, said track circuit including the rails of a block in advance of the train controlling member, said member comprising a normally magnetic sectional conductor adapted to be energized to form a magnetized conductor, each 105 track circuit including connections for influencing a train controlling member in a block behind for energizing action and for determining by the presence or absence of current in the local block the condition of a track circuit ahead. 110
- 30 10. In an electrical train control system, a series of blocks each comprising a section of trackway and a normally open circuit including the rails thereof and adapted to be closed by the bridging of the rails by the 115 rolling stock, and each having arranged therein a train controlling member, said track circuit including the rails of a block in advance of the train controlling member, each 120 train controlling member comprising a normally magnetic conductor consisting of a sectional bar having electro-magnets connected with the respective sections thereof and connected in parallel with the track cir- 125
- 35 4. In an electrical train control system, a series of blocks each provided with a normally open train controlled track circuit therein and each having a train controlling member therein, said track circuit including the rails of a block in advance of the train controlling member, said member comprising a rail consisting of conducting sections, each having an electro-magnet connected 130 therewith, said magnets being connected in parallel with the circuit in which said rail is arranged and energizable by the closing of said circuit to convert said rail from a magnetic to a magnetized conductor.
- 40 5. In an electrical train control system, a series of blocks each provided with a normally open train controlled track circuit adapted to be closed by the bridging of the track rails by the rolling stock and including said rails therein, and each of said blocks having a train controlling member therein, said track circuit including the rails of a block in advance of the train controlling member, said member normally constituting a magnetic conductor and being energizable by the closing of the track circuit in which it is arranged to form a magnetized conductor. 135
- 45 6. In an electrical train control system, a series of blocks each provided with a normally open train controlled track circuit adapted to be closed by the bridging of the track rails by the rolling stock and including said rails therein, and each of said blocks having a train controlling member therein, said track circuit including the rails of a block in advance of the train controlling member, said member comprising a rail consisting of spaced plates each having an electro-magnet arranged therein, said mag- 140

cuit in which it is arranged, each track circuit including connections for energizing a train controlling member in a block behind for a train controlling action and determining by the presence or absence of current in the local block the condition of a track circuit ahead.

11. In an electrical train controlling system, a series of blocks arranged within main 10 and branch lines, and each including a normally open circuit adapted to be closed by the rolling stock, means for connecting the track circuits of a portion of the main line with or disconnecting the same from the track circuits in the branch line, a train controlling member in each circuit, said circuit including the rails of a block in advance of the train controlling member, and means arranged in the main and branch lines for 20 regulating the speed of a train approaching the switch point.

12. In an electrical train controlling system, a series of blocks arranged within main and branch lines, and each including a normally open circuit adapted to be closed by the rolling stock, means for connecting the track circuits of a portion of the main line with other circuits in said line or with the circuits in the branch line, a train stopping 25 device in each block adapted to be energized for action by the presence of a train in the immediate block, and speed controlling devices in the main and branch lines for governing the speed of a train approaching the 30 switch point.

13. In an electrical train control system, block circuits adapted to be closed by rolling stock upon the block thereof, a train governing device in each block, each block circuit 40 including the rails of a block in advance of the train governing device, said governing device forming a magnetic conductor when said circuit is open or inoperative and a magnetized conductor when said circuit is 45 closed and operative, and a train controlling circuit on the locomotive including an electro-magnet repelled or retracted by the condition of said train governing device.

14. In an electrical train control system, 50 and in combination with track circuits governed by the rolling stock and including a controlling member in each block forming a magnetic or magnetized conductor under different conditions in the coöperating circuit, each track circuit including the rails of a block in advance of the controlling member therein, train governing means upon the locomotive including a circuit embodying a generator actuated by the running 55 gear of the locomotive, train controlling devices, solenoids for controlling the same, and an electro-magnet controlling the governing circuit and normally supported above and free from contact with said conductor

and adapted to be attracted or repelled by 65 said conductor.

15. In an electrical train control system, and in combination with train stopping and speed controlling devices governed by track conditions to form magnetic or magnetized 70 conductors, train controlling and stopping circuits on the locomotive, a generator for supplying said circuits and actuated by the running gear of the locomotive, and electro-magnets governing said circuits and including 75 circuit closing members comprising magnets normally supported above the trackway for travel clear of said conductors and adapted to be attracted or repelled by the respective conductors.

16. An electrical train control system embodying block circuits each including a train controlling device comprising a temporary magnet influenced by the energization of a circuit in advance of the one in which it is 80 arranged, said magnet being arranged to present its north pole in operative position, and controlling means upon a train to be controlled, said means including a temporary magnet presenting its north pole in 85 operative relation to the corresponding pole of the first-named magnets.

17. An electrical train control system embodying track circuits, each including a train control device comprising a temporary 95 magnet influenced by the energization of a circuit in advance of the one in which it is arranged, and controlling means upon a train to be controlled also including temporary magnets, said magnets being arranged 100 to present like poles in facing relation when brought into proximity to each other.

18. An electrical train control system embodying track circuits, each including a train controlling device comprising a magnet 105 influenced by the energization of a circuit in advance of the one in which it is arranged, said magnet comprising a bar of magnetic material and magnets disposed beneath said bar with their north poles in 110 proximity thereto, and controlling means upon a train to be controlled for coöperation with the block magnets, said means including a temporary magnet presenting its north pole in operative relation to the magnetic bars of the first-named magnets.

19. An electrical train controlling system embodying block circuits, each including a temporary magnet consisting of a magnetic conductor convertible to a magnetized conductor upon the energization of a block circuit in advance of the circuit in which it is arranged, and controlling means upon a train to be controlled for coöperation with said magnetic conductors, said means including a temporary magnet of a character 120 to be influenced only when the first-named conductors are in demagnetized condition.

20. An electrical train control system embodying a plurality of block circuits, each including a train controlling device comprising a magnet adapted to be energized by the energization of a block circuit in advance of that in which it is arranged and a coöperating temporary magnet upon the train to be controlled, the said magnets being normally arranged to present energized like poles for a non-influencing action, and

the said block magnets being deenergizable to attract the train magnets for a controlling action.

In testimony whereof I hereunto affix my signature in the presence of two witnesses.

JOSEPH E. ANDERSON.
